(57) **CLAIM**

The ornamental design for a cowling on a deployable thruster for a marine vessel, as shown and described.

DESCRIPTION

FIG. 1 is a perspective view of a cowling on a deployable thruster for a marine vessel.

FIG. 2 is a side view thereof.

FIG. 3 is an opposite side view thereof.

FIG. 4 is a front view thereof; and,

FIG. 5 is a bottom view thereof.

The broken lines illustrate the portions of the cowling on a deployable thruster for a marine vessel that form no part of the claimed design.
